(57) **CLAIM**

The ornamental design for a luggage shell with surface configuration, as shown and described.

DESCRIPTION

This application is an application for reissue of U.S. Design Pat. No. D. 889,837, which issued on Jul. 14, 2020, from U.S. Design application Ser. No. 29/664,241, which was filed on September 24, 2018, and claims the benefit of EUIPO Community Design No. 004952505-0011, filed Mar. 22, 2018, and EUIPO Community Design No. 004952505-0012, filed Mar. 22, 2018. The disclosure of the above applications is incorporated herein by reference.

FIG. 1 is a perspective view of the luggage shell with surface configuration in a first environment showing a representative luggage shell in broken lines;

FIG. 2 is a front view thereof;

FIG. 3 is a rear view thereof;

FIG. 4 is a right side view thereof;

FIG. 5 is a left side view thereof;

FIG. 6 is a perspective view of the luggage shell with surface configuration in a second environment showing a representative piece of luggage in broken lines;

FIG. 7 is a front view thereof;

FIG. 8 is a rear view thereof;

FIG. 9 is a right side view thereof; and,

FIG. 10 is a left side view thereof.

The broken lines showing luggage are for the purposes of illustrating environment and forms no part of the claimed design.

1 Claim, 10 Drawing Sheets

Matter enclosed in heavy brackets [ ] appears in the original patent but forms no part of this reissue; matter printed in italics indicates the additions made by reissue.
